Peter J. Warren
By his Attorney
John H. Ruege

UNITED STATES PATENT OFFICE

PETER J. WARREN, OF BROOKLYN, NEW YORK

SAFETY BELT

Application filed March 21, 1930. Serial No. 437,668.

This invention relates to improvements in safety belts, the principal object of the invention being to provide a belt of this character which upon being subjected to a predetermined strain will come apart to release itself from the body of the wearer.

A further object of the invention is to provide a safety device for connecting the parts of a belt together, which device will maintain the belt intact under ordinary strain, but which when subjected to a strain exceeding a predetermined limit will permit the parts of the belt to become separated.

With the foregoing and other objects in view which will appear as the description proceeds, the invention consists in the novel features of construction and combination of parts which will be more fully described hereinafter and particularly pointed out in the claims.

In the drawing accompanying this specification,

Fig. 1 is a perspective view of a belt embodying the features of the present invention.

Fig. 2 is a perspective view of the parts of the improved safety device showing the same separated and broken away from the belt; and

Fig. 3 is a fragmentary sectional elevation of one of said members.

Belts of the type commonly known as "Sam Browne" belts have been found very satisfactory for the purposes of police and other officers, because they afford a convenient and desirable means of carrying necessary equipment. The use of such belts, however, has been accompanied by a serious disadvantage, in that it has occasionally hap-

pened that an officer has been attacked from behind, his assailant finding it a comparatively easy matter to prevent him from turning around by merely taking a firm grip on the back portion of the belt. It has happened that an officer has lost his life, in this way, because of his inability to shake himself loose from his assailant's grasp. The object, therefore, of the present invention is to overcome this disadvantage by providing a belt by means of which an officer can readily

free himself from such a disadvantageous position.

The belt shown herein is in the form of what is commonly known as a "Sam Browne" belt and the waist portion thereof is made up of three parts, 1, 2 and 3 respectively. The portion 1 is secured at one end to the bar of the buckle 4 in the usual manner, while the part 2 is provided with perforations extending over a portion of its length for engagement with the hook of said buckle. Each of said portions 1 and 2 carries at its end remote from the buckle one member of the improved safety device to be hereinafter described, while the portion 3 of the belt carries at its opposite ends the co-operating members of said safety device. The shoulder strap of the belt is separated about midway of its length into two portions 5 and 6, respectively, said portions being each connected at one end by means of the usual rings 7 and 8 to the belt portions 1 and 3, respectively, said strap portions each carrying at its opposite end a co-operating member of the improved safety device.

The safety device comprises a pair of sheet metal plates 9 and 10, respectively, each bent to form a pair of leaves adapted to receive between them an end of one of the belt portions, said leaves being secured to their respective belt portions by means of rivets 11. The portion of the member 10 which connects its leaves is cut away centrally thereof to form a recess 12 while the corresponding portion of the member 9 is cut away adjacent its opposite ends so as to leave a projecting male portion 13 adapted to fit within the recess 12 after the manner of a hinge. The projecting portion 13 thus forms between it and the end of the belt portion to which it is secured a housing in which is mounted a spiral spring 14 under tension, the opposite ends of said spring bearing against a pair of balls 15 mounted in the ends of the housing, the metal of the housing wall being turned over inwardly sufficiently to retain said balls therein in slight projecting position.

It is believed that the operation of the device will be clear from the foregoing. The

ends of the belt portion carrying cooperating members 9 and 10 are brought together and the male portion 13 inserted into the recess 12, some pressure being exerted to cause the edges of the recess to force the balls inward against the tension of the spring. When the balls have passed said edges, the tension of the spring will force them outward so that they will act in the nature of a pintle and retain the parts together under all normal strain to which the belt may be subjected in use. However, should an attempt be made to detain the wearer by taking hold of the belt at any portion thereof, the abnormal pressure which would naturally be exerted either by the wearer in an effort to free himself, or by an assailant to detain him would result in a separation of the parts of the safety device, thus permitting the belt to come apart and release the wearer.

Having thus described my invention, what I claim is:

1. A safety belt comprising a plurality of waist engaging portions and means normally securing said portions together and automatically separable under a predetermined force to cause separation of said belt portions.
2. A safety belt comprising a plurality of waist engaging portions, a shoulder strap secured at its opposite ends to said waist engaging portions, said shoulder strap being formed of separable portions, and means respectively connecting the waist engaging portions and shoulder strap portions and automatically separable under abnormal force to cause separation of said waist portions and shoulder strap portions.

In testimony whereof I have signed my name to this specification.

PETER J. WARREN.
